UNITED STATES PATENT OFFICE

161,005

TIE SLIDE

Alexander Corpora, Los Angeles, Calif.

Application February 6, 1950, Serial No. 7,759

Term of patent 3½ years

(Cl. D17—10)

To all whom it may concern:

Be it known that I, Alexander Corpora, of Los Angeles, county of Los Angeles, State of California, have invented a new, original, and ornamental Design for a Tie Slide, of which the following is a description, reference being had to the accompanying drawing, forming a part hereof.

Figure 1 is a top edge view, Figure 2 is a front elevation and Figure 3 is a side edge view of the tie slide showing the new design. Figure 4 is a vertical, axial section of the slide.

I claim:

The ornamental design for a tie slide, substantially as shown.

ALEXANDER CORPORA.
